UNITED STATES PATENT OFFICE

ERNEST DICKEY, OF DAYTON, OHIO, ASSIGNOR TO DELCO-LIGHT COMPANY, OF DAYTON, OHIO, A CORPORATION OF DELAWARE

ELECTRICAL APPARATUS

Application filed July 29, 1929. Serial No. 382,051.

The present invention relates to electrical generating systems.

Generating systems used for household purposes or farm lighting or the like are often called upon to serve translating devices which require frequent operation such as a refrigerating apparatus. The capacity of these translating devices are such whereby it is desirable to supply some of the energy directly from the dynamo of the lighting system, however, due to the frequent occurrence of a demand for energy by the translating device, it would be uneconomical to render the dynamo operative upon every demand by the translating device because of the energy required in starting the dynamo.

One of the objects of the present invention is to provide an electrical generating system including electrical apparatus, such as a dynamo, and a storage battery, which system will be rendered operative only upon intermittent demands for current by a work circuit.

In carrying out this idea of the invention it is a further object to provide means for causing the storage battery to supply a demand for current by the work circuit and for causing the system to be rendered operative to supply the current demand upon alternate demands for current by the work circuit. One manner of preventing the operation of the system except upon, for example, every other demand for current is to provide a switch responsive to a demand for current by the work circuit for controlling the necessary circuits for rendering the system operative, which switch is adapted to render the system operative once for every two operations thereof.

It is a further object to provide for supplying the storage battery with charging current by the dynamo in an amount equal to or more than one-half of its total output while the work machine contained in the work circuit is operating therefrom.

Further objects and advantages of the present invention will be apparent from the following description, reference being had to the accompanying drawing, wherein a

preferred form of the present invention is clearly shown.

In the drawing:

The figure in the drawing is a wiring diagram illustrating the present invention.

Referring to the drawing 20 designates generally a prime mover herein shown, for the purpose of illustration, as an internal combustion engine having a shaft 21 which drives an electrical apparatus or dynamo 22 having main brushes 23 and 24 connected to the armature of the dynamo, and having a starting series field winding 25 and a shunt field winding 26.

The ignition apparatus comprises an ignition coil primary 30, an ignition timer 31 and an ignition coil secondary 32 which is connected to an engine spark plug 33.

A choke 38 forming a proper mixture of gasoline and air for starting the prime mover, and a throttle 39 for regulating the speed of the prime mover, are adapted to be actuated by the controls 40 and 41 respectively.

The dynamo 22 functions as a motor or as a generator, and is adapted to rotate the shaft 21 of the prime mover 20, when acting as a starting motor, receiving current from a storage battery 45. During the starting of the prime mover 20, the current through the series winding 25 and the shunt winding 26 is cumulative to produce a sufficient starting torque for cranking the prime mover.

When the load demand on a lighting circuit 48 is less than a predetermined value, the storage battery 45 is adapted to supply such demand. The current to the lighting circuit 48 will flow from the battery 45 through the following circuit: battery 45, wire 50, wire 51, wire 52, winding 53 of control 41, wire 55, contacts 57 and 58, service main 59, small translating device or lights 60, service main 61, current coil 62 of a starting switch relay 63, wire 65 and wire 66 to the other side of the battery.

A low voltage cut-out 70 is adapted to separate contacts 57 and 58 when the voltage of the battery is abnormally low. The low voltage cut-off 70 includes a pivoted armature 71 which carries the contact 58, and a magnet coil 72 having its ends connected across the

lighting circuit 48 in parallel with the translating devices 60. When the voltage of the battery 45 is less than a predetermined low value, the coil 72 will not be energized sufficiently to hold the armature 71 in the position shown in the drawing. Thus the armature 71 will descend by gravity to separate contact 57 from contact 58, thereby interrupting the flow of current from the battery 45 to the work circuit 48.

When there is a load demand for current by the lighting circuit 48 in excess of a predetermined value, for example seven amperes, the ampere turns of the current coil 62 of the starting switch relay 63 are sufficient to lift the armature 75 upwardly to engage a contact 76 with a contact 77. The closing of contacts 76 and 77 allows current to flow from the battery 45 through the ignition and various other circuits necessary for rendering the prime mover 20 automatically operative to drive the dynamo 22 to supply current to the work circuit 48 and battery 45. The circuit from the battery 45 to the ignition is as follows: battery 45, wire 50, wire 80, blade 81, bimetallic thermostatic blade 82, wire 83, contacts 77 and 76, wire 85, ignition coil primary 30, timer 31, wire 87, wire 88, wire 89, series winding 90 of a reverse current relay 91 and wire 66 to the other side of the battery. The closing of contacts 76 and 77 also allows current to flow from the battery 45 to a magnet coil 92 of a starting switch 93. The starting switch 93 includes the coil 92 and a pivoted armature 94 which carries a contact 95. The energizing of the coil 92 will cause the armature 94 to be drawn upwardly to engage contact 95 with a contact 96. The circuit from the battery 45 through the coil 92 is as follows: battery 45, wire 50, wire 80, blades 81 and 82, wire 83, contacts 77 and 76, wire 85, wire 98, magnet coil 92, wire 99, wire 89, winding 90, and wire 66 to the other side of the battery.

The closing of contacts 95 and 96 of the starting switch 93 establishes a cranking circuit between the battery and the dynamo which is as follows: battery 45, wire 50, winding 100 of the control 40, wire 101, series winding 25 of dynamo 22, wire 102, dynamo 22, wire 103, contacts 96 and 95, wire 89, series winding 90 of reverse current relay 91 and wire 66 to the other side of the battery.

The current flowing through the series winding 90 of the reverse current relay 91 during cranking is adapted to magnetize the frame of relay 91 including side plates or pole pieces 105 and 106 whereby said plates 105 and 106 will be, for example, north and south poles respectively. The relay 91 also includes a rocking armature 108 having a shunt winding 109, which winding is connected across the battery 45. The circuit from the battery 45 to the shunt winding 109 is as follows: battery 45, wire 50, wire 80,

blades 81 and 82, wire 83, wire 111, shunt winding 109, wire 112, contacts 96 and 95, wire 89, series winding 90 and wire 66 to the other side of the battery. The armature 108 includes side plates 115 and 116 which plates are adapted to be magnetized north and south poles respectively by shunt winding 109. When no current is flowing in the windings 90 and 109, armature 108 is in the position shown, it being resiliently held in such position by a spring (263). When the current flows through the series winding 90 during cranking, like poles of the relay frame and armature will repel and thus urge the armature 108 in the same direction as the spring 263 turns it, whereby contact 120 engages contact 121.

The engagement of contacts 120 and 121 allows current to flow from the battery through the following circuit when contacts 76 and 77 of relay 63 are closed: battery 45, wire 50, wire 80, blades 81 and 82, wire 83, contacts 77 and 76, wire 125, conductor 261, contacts 120 and 121, wire 126, wire 127, shunt winding 128 of the starting switch relay 63, then back to the opposite side of the battery through the winding 62 and wires 65 and 66; also current from wire 126 flows through wire 129 to pre-heater 130 grounded at 131, the circuit being completed through the ground 132, wire 133, wire 88, wire 89, winding 90 and wire 66; and current also flows from wire 126 through a heating coil 135 of a cranking cut-out 136, wires 137 and 138, wire 89, winding 90 and wire 66 to the other side of the battery. The pre-heater 130 is adapted to heat the starting fuel mixture for the prime mover 20. During cranking operation the current flows through the shunt winding 128 of relay 63 to cooperate with the current coil 62 to insure maintaining of contact between contacts 76 and 77.

The flow of current through the magnet coil 100 of the choke control 40 tends to raise the control plunger 140 upwardly which plunger carries the choke 38. The upward movement of the plunger 140 will cause the choke 38 to shut off the air passage 141, thus decreasing the quantity of air and consequently allowing a greater volume of gasoline to pass through a pipe 143 and into the carburetor to thus provide a relatively rich starting fuel mixture for the prime mover. The control 40 is adapted to function for a short interval, namely, only when a heavy demand for current is made on the battery 45 during cranking which heavy demand is present for a short interval.

Thus when there is a predetermined demand by the lighting circuit 48 the prime mover 20 will be started by supplying ignition thereto and cranking by the starting series field winding 25 in conjunction with the shunt field winding 26 of the dynamo 22.

The starting being aided by enriching the fuel mixture and heating such mixture.

If the prime mover 20 should not start within a certain length of time, abnormal discharge of the battery is prevented by the cranking cut-out 136 which includes the blade 81 and bimetallic thermostatic blade 82 and the heating coil 135. The blade 81 is fixed at 145 and has a non-conducting block 146 secured thereto. The blade 81 is urged downwardly by a spring 147 to engage a flanged end 148 of the bimetallic thermostatic blade 82, said blade being fixed at 149. The thermostatic blade 82 is in heat receiving relation to the heating coil 135. While the prime mover is cranking current is passing through this heating coil as previously described. If the cranking of the prime mover should continue for an abnormal period, for example, one to two minutes, the thermostatic blade 82 will be heated sufficiently to cause it to bow to the right, as viewed in the drawing, until the flanged end 148 moves to the right far enough to break its engagement with the blade 81 and is then retained in a shoulder 150 of the non-conducting block 146 by the downward movement of the blade 81. The separation of blades 81 and 82 will interrupt the flow of current to the ignition shunt winding 128 of relay 63, shunt winding 109 of reverse current relay 91, heating coil 135 of the cranking cut-out 136, the fuel pre-heating coil 130 and the coil 92 of starting switch 93. When coil 92 is deenergized the armature 94 will descend by gravity to separate contact 95 from contact 96, thus the starting circuit will be interrupted.

During normal operation, when the prime mover becomes self-operative and attains a certain speed the dynamo will function as a differentially wound generator, the current flowing from the dynamo to the battery over the cranking circuit. The current flowing through the series winding 90 of the reverse current relay 91 will be reversed from that during cranking, since this winding is in series with the dynamo 22 and battery 45 and in series with the work circuit 48. This causes a reversal of magnetism in the relay side plates 105 and 106, and consequently the like pole of the armature side plates 115 and 116 will be moved away from the like pole of the relay side plates causing the armature 108 to pivot and to separate contact 120 from contact 121 and cause contact 155 to engage a contact 156. Thus the flow of current through the pre-heater 130, heating coil 135 and winding 128 of relay 63 will be interrupted, the contacts 76 and 77 of relay 63 then being controlled entirely by the winding 62.

The closing of contacts 155 and 156 allows current to flow from the dynamo 22 to a magnet coil 160 of a series field winding shorting switch 161. The switch 161 also

includes armature 162 which carries a contact 163. The energizing of coil 160 will draw the armature 162 upwardly to engage contact 163 with a contact 164. The current from the dynamo through the magnet coil 160 is as follows: dynamo 22, wire 102, series winding 25, wire 101, magnet coil 100, wire 50, wire 80, blades 81 and 82, wire 83, contacts 77 and 76, wire 125, connector 262, contacts 155 and 156, wire 165, magnet coil 160, wire 138, contacts 95 and 96, wire 103 to the other side of the dynamo.

The closing of contacts 163 and 164 allows current to flow from the brush 24 of the dynamo 22 through the wire 167, contacts 163 and 164, wire 168, and wire 51 which joins with wire 50 and thus short-circuits the series field winding 25 of the dynamo 22 and the choke coil 100 of the control 40 since the circuit just described offers less resistance than the circuit through the series field 25 and coil 100.

The dynamo 22 then functions as a shunt wound generator and supplies current to the translating device or lights 60 in the lighting circuit 48 and supplied charging current to the battery 45. The flow of current from the dynamo 22 through the work circuit is as follows: dynamo 22, wire 167, contacts 163 and 164, wire 168, wire 52, magnet coil 53 of the throttle control 41, wire 55, contacts 57 and 58, service main 59, translating devices 60, service main 61, current coil 62 of relay 63, wire 65, wire 66, series winding 90, wire 89, contacts 95 and 96 and wire 103. The flow of current from the dynamo 22 through the battery charging circuit is as follows: dynamo 22, wire 167, contacts 163 and 164, wire 168, wire 51, wire 50, battery 45, wire 66, series winding 90, wire 89, contacts 95 and 96 and wire 103.

When the dynamo 22 is operative to supply current to the battery 45 and work circuit 48, the control 41 functions to regulate the speed of the prime mover 20 to drive the dynamo 22 to supply current in accordance with the demand for current by the work circuit 48. The control 41 includes the winding 53, a plunger 170 operatively connected with the throttle 39, a spring 171 interposed between the control housing 172 and the plunger 170, and a weight 173. Current flowing through the winding 53 tends to draw the plunger upwardly to open the throttle, while the spring 171 tends to oppose the winding 53 to move the plunger 170 downwardly to close the throttle. As the current through the winding 53 increases the ampere turns are thereby increased, consequently the magnetic effect of the winding 53 will be increased sufficiently to move the plunger 170 upwardly to open the throttle to such an extent as will be necessary to accelerate the prime mover 20 to drive the dynamo 22 to supply current in accordance to the demand by the work circuit.

As the flow of current through the winding 53 is decreased the opposing force of the spring 171 will be sufficient to move the plunger 170 downwardly to close the throttle 5 proportionally to the load demand. The weight 173 is adapted to slightly over-balance the weight of the plunger 170 and hold the same in contact with the spring 171 when the winding 53 is deenergized. By this arrangement the plunger will be moved upwardly or downwardly by a steady movement depending upon the increase or decrease of current in the winding 53. Since the winding 53 is disposed in the supply circuit to the service mains, the speed of the prime mover will be controlled in accordance to the demand by the work circuit.

When it is desired to supply a charging current to the battery 45 and there is no load demand by the work circuit 48 for rendering the prime mover automatically operative, an actuating and locking device 175 may be manually operated to engage contact 76 with contact 77 to complete the necessary electrical circuits for starting the prime mover. The locking device 175 includes the plunger 176, cross-rod 177 which is pivoted at 178, said cross-rod having an arm 179 secured thereto and a locking clasp 180. The downward movement of the arm 179 will cause the plunger 176 to urge the armature 75 upwardly to engage contact 76 with contact 77. The locking clasp 180 is adapted to receive the arm 179 to hold the device in position to prevent contact 76 from becoming separated from contact 77.

In the event that the prime mover 20 is idle, and there is a demand for current by the power circuit 200, a switch 202 is adapted to respond to such demand. However, the relay 202 is adapted for rendering the prime mover 20 operative only on intermittent demands by the power circuit although the relay is actuated every time there is a demand for current. In the preferred embodiment illustrated the relay will cause the prime mover 20 to be rendered operative only on every other operation thereof.

An electric motor 204, for example, is shown connected across the power circuit 200 and is used, for example, for driving a refrigerator compressor, and is controlled by the switch 205. The switch 205 includes a bellows 207 having a pipe 208, which pipe may be connected to any desirable part of the refrigerating control system. As the pressure within the control system reaches a predetermined value, the bellows 207 will actuate a rod 265 about pivot 266 which in turn moves member 209 to actuate member 269 through pivots 267 and 268 to engage a contact 210 with a contact 211. For the purpose of illustration, I have shown a pressure responsive switch, however, it is to be

understood that any switch whether automatic or manually operated may be used.

The closing of contacts 210 and 211 will complete a circuit between the motor 204 contained in the power circuit 200 and the battery 45. The circuit from the battery 45 through the power circuit 200 is as follows: battery 45, wires 50, 51 and 52, winding 53 of control 41, wire 55, contacts 57 and 58, service main 59, service main 215 including contacts 210 and 211, wire 217, service main 220 including current coil 221 to the other side of the battery.

The energization of current coil 221 is adapted to cause the operation of the relay 202. The relay 202 is adapted to control the necessary circuits for rendering the system operative, and in the preferred embodiment it renders the system operative on every other operation of the relay. The relay 202 includes a pivotedly mounted armature 225a which has a non-conducting block 225 secured thereto which block carries a finger 226 pivotedly mounted thereon and having a detent 227, and a movable cam 229. The cam 229 includes a plurality of flat portions 230, a plurality of arcuate portions 231 about the periphery thereof, and a plurality of studs 232, the cam being adapted to rotate on a stationary pin 233. When the coil 221 becomes energized it will draw the armature 225 upwardly to thereby engage a contact 245 with a contact 246, and also to cause the cam 229 to rotate one-eighth of a turn in the direction indicated on the drawing. As the armature 225 moves upwardly, the detent 227 will engage one of the studs 232 to thus rotate the cam. As shown in the drawing one of the flat portions 230 of the cam 229 is engaging a blade 235. When the cam 229 rotates, as just described, one of the outwardly extending arcuate portions 231 will then engage the blade 235 and cause the same to move to the right, as viewed in the drawing, thereby engaging the blade 235 with a contact 236.

The closing of contacts at 235 and 236 and contacts 245 and 246 will complete the necessary electrical circuits for rendering the prime mover operative including a circuit through the magnet coil 92 of starting switch 93, ignition, pre-heater, shunt winding 128 of relay 63, and heating coil 135 of cranking cut-out 136. The circuit from the battery 45 to the contacts 235 and 236 and the circuit for starting the prime mover is as follows: battery 45, wires 50 and 80, blades 81 and 82, wires 83, 111, 240, contacts 245 and 246, connecting point 247, contacts 235 and 236, blade 234 to connecting point 249, wire 250 to armature 75 where the wire 250 joins wires 85 and 125, the current flowing through wires 85 and 125 to the various circuits necessary for starting the prime mover as previously described.

After the prime mover 20 becomes self-

operative, the dynamo 22 will supply current to the motor 204 over the following circuit: 5 dynamo 22, wire 167, contacts 163 and 164, wires 168 and 52, winding 53 of control 41, wire 55, contacts 57 and 58, service main 59, service main 215 including contacts 210 and 211, wire 216, motor 204, wire 217, service main 220 including current coil 221, wire 66, winding 90 of relay 91, wire 89, contacts 95 and 96, and wire 103 to the other 10 side of the dynamo. The dynamo 22 may be regulated so that when current is being supplied to the device 204 an amount of current equal to or more than one-half of the total output of the dynamo is being stored in the battery 45, the current flowing to the battery over the battery-charging circuit previously described. In this manner the battery 45 is always maintained in operating 15 condition to operate the motor 204 when supplying current to the motor.

When the demand for current by the power circuit 200 ceases, the current coil 221 becomes deenergized, thereby causing the armature 225 to descend to separate contacts 245 and 246, thereby interrupting the necessary electrical circuits for maintaining the prime mover operative. As the armature 225 descends the finger 226 will move downwardly 20 while the detent 227 will be urged to the right, as viewed in the drawing, by a spring 255 to engage a stud 232. Thus it will be noted that on the next demand for current by the power circuit 200, the cam 229 will again rotate one-eighth turn and in so doing 25 one of the flat portions 230 of the cam 229 will again engage the blade 234, thus the blade 234 will assume the position shown in the drawing, and in so doing will separate contact 235 from contact 236. The separation of contacts 235 and 236 will interrupt the necessary circuits for starting the prime mover 20 although the contacts 245 and 246 are closed. The battery 45 will then supply 30 the demand by the motor 204 over the circuit previously described.

From the foregoing it will be apparent that I have provided an electrical generating system including a dynamo and a storage battery, which system is adapted to be rendered 35 automatically operative only upon intermittent demands for current by the work circuit. One of the advantages of a system operable only on intermittent demands is that the number of starting operations is decreased, thereby preventing a heavy drain upon the battery by numerous demands for cranking current. Another advantage is that less operation of the system is required, thus causing a saving of fuel.

While the form of embodiment of the invention as herein disclosed, constitutes a preferred form, it is to be understood that other forms might be adopted, all coming within the scope of the claims which follow.

What is claimed is as follows:

1. An electrical generating system comprising, in combination; an intermittently operating work circuit; a source of current connected with the work circuit; a second source of current adapted to supply current to the work circuit; and means adapted to render the second source of current operable only on alternate demands for current by the work circuit. 70

2. An electrical generating system comprising, in combination; an intermittently operating work circuit; a source of current connected with the work circuit; a second source of current; circuit connections between the first source and the second source for rendering the second source of current operable to supply current to the work circuit; and means adapted to render the second source of current operable only on alternate demands for current by the work circuit. 80

3. An electrical generating system comprising, in combination; an intermittently operating work circuit; a source of current connected with the work circuit; a second source of current; circuit connections between the first source and the second source for rendering the second source of current operable to supply current to the work circuit; and means responsive to a demand for current by the work circuit for rendering the second source operable only on alternate demands. 90

4. An electrical generating system comprising, in combination; an intermittently operating work circuit; a source of current connected with the work circuit; a second source of current; a control circuit for rendering the second source of current operable to supply current to the work circuit; a relay for controlling the control circuit; and means responsive to a demand for current by the work circuit for causing the relay to close the control circuit only on alternate demands for current by the work circuit. 100

5. An electrical generating system comprising, in combination; an intermittently operating work circuit; a source of current connected with the work circuit; a second source of current; circuit connections between the first source and the second source for rendering the second source of current operable to supply current to the work circuit; a control circuit for controlling the operation of the second source; a relay for controlling the control circuit; and means responsive to a demand for current by the work circuit for causing the relay to close the control circuit only on alternate demands for current by the work circuit. 115

6. An electrical generating system comprising, in combination; an intermittently operating work circuit containing a translating device; a storage battery connected with 130

the work circuit; an electrical apparatus adapted to operate as a generator to supply current to the work circuit and for supplying the storage battery with charging current in 5 an amount equal to or more than one-half of its total output while the translating device is operating therefrom; and means responsive to a demand for current by the work circuit for rendering the electrical apparatus operable only on alternate demands.

7. An electrical generating system comprising in combination, an intermittently operating work circuit, a source of current connected to the work circuit, a second source 15 of current adapted to supply current to the work circuit, and means adapted to render the second source of current operative to supply current to the work circuit only after a pre-determined number of demands for current 20 by the work circuit.

8. An electrical generating system comprising in combination, an intermittently operating work circuit, a source of current connected to the work circuit, a second source 25 of current adapted to supply current to the work circuit, and means responsive to a demand for current for causing the first named source of current to supply the demand to the work circuit, said means also being arranged for causing said second source of current to supply the demand to the work circuit only after a predetermined number of demands by the work circuit.

9. An electrical generating system comprising in combination an intermittently operating work circuit, a source of current connected to the work circuit, a second source of current adapted to supply current to the work circuit, and means responsive to a demand for current adapted to render the second source of current operative to supply current to the work circuit only after the first named source of current has been rendered operative and after the cessation of the first 40 demand, said means also being arranged to render the first named source of current operative in response to a demand for current by the work circuit after said second source of current has been rendered operative to 45 supply the demand a predetermined number of times.

In testimony whereof I hereto affix my signature.

ERNEST DICKEY.
